A portion of the disclosure of this patent document contains or may contain material which is subject to copyright protection. The copyright owner has no objection to the photocopy reproduction by anyone of the patent document in exactly the form it appears in the Patent and Trademark Office patent file or records, but otherwise reserves all copyrights whatsoever.

FIG. 1 depicts an isolated perspective view of a pocket stabilizer for a lacrosse head according to an embodiment of the disclosure;

FIG. 2 is an isolated front view of the lacrosse head pocket stabilizer depicted in FIG. 1;

FIG. 3 is an isolated rear view of the lacrosse head pocket stabilizer depicted in FIG. 1;

FIG. 4 is an isolated top view of the lacrosse head pocket stabilizer depicted in FIG. 1;

FIG. 5 is an isolated bottom view of the lacrosse head pocket stabilizer depicted in FIG. 1;

FIG. 6 is an isolated right-side profile view of the lacrosse head pocket stabilizer depicted in FIG. 1; and,

FIG. 7 is an isolated left-side profile view of the lacrosse head pocket stabilizer depicted in FIG. 1.

The broken lines in the figures show an environment for the pocket stabilizer for lacrosse head that forms no part of the claimed design.
